UNITED STATES PATENT OFFICE.

ANGUS R. GROSS, OF BALTIMORE, MARYLAND.

DESIGN FOR A PARKING-LIGHT FOR AUTOMOBILES.

57,640.

Specification for Design.

Patented Apr. 26, 1921.

Application filed October 19, 1920. Serial No. 418,110. Term of patent 14 years.

To all whom it may concern:

Be it known that I, ANGUS R. GROSS, a citizen of the United States, residing at Baltimore, State of Maryland, have invented a new, original, and ornamental Design for a Parking-Light for Automobiles, &c., as shown in the accompanying drawing, forming part of this specification.

In said drawings:—Figure 1 is a side

view of the lamp casing, and Fig. 2 is an end view thereof.

The striking features of the design are the T shaped casing and projecting jeweled ends.

I claim—

The ornamental design for a parking light for automobiles, substantially as shown.

ANGUS R. GROSS.
